[57] CLAIM

The ornamental design for a covered food container, as shown.

DESCRIPTION

FIG. 1 is a top plan view of a covered food container showing our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a bottom plan view thereof; and

FIG. 7 is a fragmentary cross sectional view thereof taken on line 7—7 of FIG. 1 and enlarged for clarity of illustration.

FIG. 1

FIG. 2

FIG. 3

FIG. 4

FIG. 5

FIG. 6

FIG. 7
